UNITED STATES PATENT OFFICE

107,464

DESIGN FOR A DRINKING FOUNTAIN

Harry R. Trout, Pittsburgh, Pa., assignor to Standard Sanitary Manufacturing Company,
Pittsburgh, Pa., a corporation of New Jersey

Application June 22, 1937, Serial No. 69,989

Term of patent 14 years

To all whom it may concern:

Be it known that I, Harry R. Trout, a citizen of the United States and residing in Pittsburgh, in the county of Allegheny and State of Pennsylvania, U. S. A., have invented a new, original, and ornamental Design for a Drinking Fountain,
of which the following is a specification, reference being had to the accompanying drawing, forming a part thereof, wherein:—

The figure is a perspective view of a drinking fountain embodying my new design.

I claim:

The ornamental design for a drinking fountain as shown.

HARRY R. TROUT.
